Term of patent 14 years

(Cl. D13—1)

FIG.1

FIG.2

FIG.4

FIG.3

FIG. 1 is a perspective view of an underground utilities service pod showing my new design;

FIGURE 2 is a side elevational view thereof;

FIGURE 3 is a top plan view thereof; and

FIG. 4 is a bottom plan view thereof.

The fragmentary non-slip surface pattern illustrated in FIGS. 1 and 3 on the drawing is understood to uniformly continue throughout the top surface of the lid member.

I claim:

The ornamental design for underground utilities service pod, substantially as shown and described.
